ASSEMBLING MECHANISM OF TYPOGRAPHICAL COMPOSING MACHINES

Vernon Charles Joseph Harrison, Timperley, England, assignor to Linotype and Machinery Limited, London, England, a limited liability company of Great Britain

Application August 1, 1935, Serial No. 34,123
In Great Britain August 10, 1934

6 Claims. (Cl. 199—27)

This invention relates to typographical composing machines such as those known commercially under the registered trade-mark "Linotype", wherein matrices, released individually from a magazine in order of composition, are assembled in line, and the line of composed matrices transferred to the casting mechanism.

In machines of this kind, the matrices, on release from the magazine, are received in the so-called assembler elevator provided with rails on which the matrices are supported by their projecting ears and with matrix retaining pawls which engage behind the ears of the matrices as they enter the assembler elevator. These retaining pawls normally serve to prevent displacement of the last composed matrix of the line during the movement of the assembler elevator in known manner from the assembling position to the line transfer position, as the matrix ears lie approximately flush with the following edge of the matrix and remain in engagement with the shoulders of the pawls until the line of matrices is moved along the assembler channel by the line transfer fingers. In the case of thick or display matrices, however, the matrix ears may be located so far in advance of the following edge of the matrix that they are not supported by the retaining pawls during the movement of the assembler elevator. According to the invention this difficulty is avoided by providing a form of pawl which will automatically move inwardly into engagement with an ear of the last composed matrix of the line, irrespective of the position of that ear relatively to the following edge of the matrix.

One constructional form of the invention is illustrated in the accompanying drawings, in which:—

Figure 1 is a front elevation, partly broken away, of an assembling mechanism with the said constructional form of the invention applied thereto, and

Figure 2 is a plan view of the parts shown in Figure 1.

The assembling mechanism illustrated in the drawings is of known form, comprising an assembler elevator 1 in which matrices, released from the magazine (not shown) in order of composition are stacked in line by a rotating star wheel 2, against the face of a line resistant finger 3. When a complete line has been assembled in the elevator 1, the elevator is moved upwardly between guides 4, 5 on the fixed front plate 6 of the machine, to be transferred to the casting mechanism by the line transfer

fingers 7, 8. Ordinarily, a pair of matrix retaining pawls, such as the pawl 10 shown in Figure 2, are arranged to engage behind the ears of the matrices as they enter the assembler elevator 1, and serve also to retain the last composed matrix in position during the upward movement of the elevator 1.

As stated above, however, when a display matrix 12 is assembled at the end of a line, its ears 13 are located so far within the channel 10 of the assembler elevator 1 that the retaining pawls as heretofore constructed can no longer serve the last-mentioned purpose, and the present invention provides means for preventing displacement of such a matrix regardless of the position of its ears.

According to the constructional form of the invention illustrated, the matrix retaining pawl 15 in the rear wall 16 of the assembler elevator 1 is formed at its inner end with a rearwardly extending arm 17 which passes through and projects rearwardly beyond a slot 18 in the said rear wall 16. The pawl is adapted to rock about a vertical pivot 19 on the wall 16, preferably near the inner end of said arm 17, and is held in normal position for engaging successive matrices as they enter the assembler by a spring 20, which holds the outer end of the rearwardly extending arm 17 against a stop 21 secured, preferably adjustably, to the front plate 6 of the machine frame, at the rear of the assembler elevator 1. This stop 21 has an inclined edge 22 which engages the pawl arm 17 and permits the pawl 15 to move inwardly under the action of its spring as the elevator 1 is moved upwardly away from the assembling position. The longitudinal arm 23 of the pawl 15 is thus held in engagement with the rear ear 13 of the last composed matrix of the line during the movement of the assembler elevator 1 away from the assembling position and is returned to the normal position by the cam action of the inclined edge 22 of the stop 21 as the assembler elevator 1 is returned to the assembling position. The slot 18 in the assembler elevator rear wall 16 in which the rearwardly extending arm 17 of the pawl 15 is accommodated, has rearwardly diverging walls to permit of the pivotal movement of the pawl, and the wall 24 of the said slot 18 serves as a stop to limit the inward movement of the pawl 15.

By the above-described arrangements, display matrices such as 12 are adequately supported during the upward movement of the elevator 1,

and the normal operation of the pawl 15 during the assembly of the line remains unaffected.

It will be understood that the constructional form of the apparatus herein described and illustrated has been chosen merely as a convenient example, and that modifications in the form of the parts may be made without departing from the invention.

Having described my invention, I declare that 10 what I claim and desire to secure by Letters Patent is:—

1. In a typographical line composing machine, the combination of an assembler having a channel wherein matrices are composed in line, the 15 said assembler being movable from line receiving to line delivering positions, a matrix retaining pawl adapted to engage an ear of a matrix at the entrance end of the channel when the assembler is in the line receiving position, and 20 means adapted automatically to move the pawl inwardly transversely of the channel during the movement of the assembler from line receiving to line delivery position, into engagement with a matrix ear located in advance of the said 25 entrance end.

2. In a typographical line composing machine, the combination of an assembler having a channel wherein matrices are composed in line, the 30 said assembler being movable from line receiving to line delivering positions, a matrix retaining pawl adapted to engage an ear of a matrix at the entrance end of the channel when the assembler is in the line receiving position, and 35 means adapted automatically to move the pawl inwardly and outwardly transversely of the channel during the movements of the assembler respectively away from and towards its line receiving position.

3. In a typographical line composing machine, 40 the combination of an assembler having front and rear walls forming between them a channel in which matrices are composed in line, said assembler being movable from line receiving to line delivering position, a matrix retaining pawl 45 pivoted in the assembler rear wall and normally urged inwardly into the said channel, an arm on the pawl passing through and projecting rearwardly beyond said rear wall, and a cam member adapted to engage said rearwardly projecting arm whereby the pawl is permitted to move 50

inwardly transversely of the channel and positively moved outwardly during the respective movements of the assembler from and to its line receiving position.

4. In a typographical line composing machine, 5 the combination of an assembler having front and rear walls forming between them a channel in which matrices are composed in line, said assembler being movable from line receiving to line delivering position, a matrix retaining pawl 10 comprising a pawl arm extending longitudinally of the said rear wall and a second arm passing through and extending beyond a slot in the said rear wall, a pivot for the said pawl located near the inner end of the said second arm, a spring 15 normally tending to project the pawl arm inwardly transversely of the channel, and a stop adapted to engage the outer end of the said second arm to limit the inward movement of the pawl arm to definite extents appropriate 20 respectively to the line receiving position and line delivering position of the assembler.

5. In a typographical composing machine, a combination according to claim 4, wherein the slot accommodating the rearwardly projecting 25 arm of the matrix retaining pawl is formed with rearwardly diverging walls, one of which walls serves as a stop for the inward movement of the pawl arm in the line delivery position.

6. In a typographical line composing machine, 30 the combination of an assembler movable vertically between line receiving and line delivering positions and having front and rear walls forming between them a channel in which matrices are composed in line, a fixed machine 35 frame member at the rear of the assembler carrying guides for the vertical movement of the assembler, a matrix retaining pawl comprising a pawl arm extending longitudinally of the assembler rear wall and a second arm passing 40 through and extending beyond a slot in the said rear wall, a pivot for the pawl located near the inner end of said second arm, a spring 45 normally tending to project the pawl arm inwardly into the channel, and a stop adjustably secured to the said machine frame member, said stop having an inclined edge adapted to engage the outer end of the said second arm.
